UNITED STATES PATENT OFFICE.

HANS FOERSTERLING AND HERBERT PHILIPP, OF PERTH AMBOY, NEW JERSEY,
ASSIGNORS TO THE ROESSLER & HASSSLACHER CHEMICAL CO., OF NEW YORK,
N. Y., A CORPORATION OF NEW YORK.

PROCESS OF MAKING CYANOGEN COMPOUNDS.

1,214,770.

Specification of Letters Patent.

Patented Feb. 6, 1917.

Application filed June 2, 1910, Serial No. 564,672. Renewed June 21, 1916. Serial No. 105,086.

To all whom it may concern:

Be it known that we, HANS FOERSTERLING, a subject of the Emperor of Germany, and HERBERT PHILIPP, a subject of the King of Great Britain, both residing at Perth Amboy, Middlesex county, New Jersey, have invented certain new and useful Improvements in Processes of Making Cyanogen Compounds, of which the following is a specification.

This invention relates to a method of making cyanogen compounds by vaporizing a metal capable of forming cyanogen compounds and reacting the vaporized metal with nitrogenous and carbonaceous matter.

In United States Letters Patent No. 993,391, dated May 30, 1911, McNitt has disclosed a method for reducing metals, based on the electrolysis of metallic compounds, the alloying of the separated metal with the cathode metal and the separating of the two metals by passing a current of inert gas through the hot alloy whereby the more volatile metal is vaporized.

We have found that, with a metal capable of forming cyanogen compounds and with nitrogen as the inert gas, the passing of the volatile metal vapors together with the nitrogen through a furnace containing carbon, easily forms cyanogen compounds.

In United States Patent No. 914,100, Acker has disclosed a process of producing cyanogen compounds by electrolyzing a molten compound of a metal, alloying the separated metal with the cathode metal, removing the alloy from the electrolytic cell and reacting on the alloyed metal with nitrogenous and carbonaceous reagents.

Our method differs from Acker's in that we first separate the volatile metal from the cathode metal and then bring the volatile metal in contact with nitrogenous and carbonaceous matter.

In the following we have described, in connection with the accompanying drawing, one way of practising our process, the features thereof being more particularly pointed out hereinafter in the claims.

The drawing is a diagrammatic sectional view of a form of apparatus illustrating one way of carrying out our process and in connection therewith we shall describe our process as applied for instance to the production of an alkali cyanid such as sodium cyanid.

We electrolyze sodium chlorid in the presence of a suitable cathode metal such as lead, in any well-known manner and obtain an alkali metal alloy, specifically sodium lead alloy, as described by McNitt in his United States Patent No. 993,391 for instance. As McNitt has fully described his cell in the patent referred to, we shall not describe it here further than that the reference numeral 1 indicates the electrolytic chamber.

2 indicates the furnace chamber.

3 indicates a transverse partition extending from side to side of the chamber 1 leaving an opening 4 at one end between the end of the partition and the wall of chamber 1, the other end of partition 3 being bent so as to form a seal 5 into which depends end wall 6 of chamber 1.

7, 7 indicate the anodes, 8 the cathode metal, molten lead for instance, 9 the electrolyte, sodium chlorid for instance, 10 a pipe for conducting an inert gas, such as nitrogen, to a point beneath the surface of the contents of furnace chamber 2 and 11 indicates a furnace for heating furnace chamber 2.

In the operation of the cell as described the sodium is separated from the chlorin, which latter passes off in the usual manner, and is alloyed with the cathode metal. The alloy is caused to circulate out of chamber 1 through seal 5 into furnace chamber 2, as described by McNitt, where it is maintained at a suitable temperature and subjected to the action of the inert gas which passes through the same, the gas carrying the sodium vapor through connection 12 into retort 13, heated in any suitable manner (not shown), the remaining portion of the molten alloy, freed from some or all of the sodium, being drawn through channel 14 and open-

ing 4 into chamber 1 where the residual metal again serves as the cathode and the operation repeated.

The sodium lead alloy is kept at such a 5 temperature in chamber 2 as to permit the inert gas, specifically nitrogen, to be introduced therein without reaction therewith so that the gas may carry off the sodium vapor as a metal *per se* as described. The retort 10 13 is kept at such a temperature that the sodium vapors combine in the presence of nitrogen and charcoal to form sodium cyanid.

The carbonaceous material in retort 3 rests 15 on a grate 15 through which the alkali cyanid, formed as described, drips into the drum 16 of the retort and is thence permitted to flow off in any suitable manner, as through outlet 17. Fresh charcoal is 20 added from time to time as required. Very little fuel is required in practising our process as the formation of cyanid takes place at not much above the temperature at which the electrolysis takes place.

25 It is to be understood that we do not limit ourselves to the process as described. The metal from which the cyanid is formed may be produced without intermediate formation of an alloy, for instance sodium chlorid 30 may be electrolyzed by a diaphragm process and the sodium directly vaporized with nitrogen; instead of blowing nitrogen into the alloy, hydrogen or other inert gas may be used and the process may be carried out in 35 two steps if desired.

Where we use the term "sodium salt" we intend to include as well a "sodium salt mixture."

What we claim as our invention is:

40 1. The method of making cyanogen compounds consisting in vaporizing a metal, capable of forming cyanogen compounds, from an alloy containing the same, and reacting upon the vaporized metal with nitrogenous 45 and carbonaceous matter.

2. The method of making cyanogen compounds consisting in vaporizing a metal, capable of forming cyanogen compounds, from an alloy containing the same, by blowing an 50 inert gas through the molten alloy and reacting upon the vapors with nitrogenous and carbonaceous matter.

3. The method of making cyanogen compounds consisting in vaporizing a metal, capable of forming cyanogen compounds, from an alloy containing the same, by passing a 55 current of nitrogen through the molten alloy and reacting upon the vapor mixture with carbonaceous matter.

60 4. The method of making cyanogen compounds consisting in electrolyzing a metallic compound containing a metal capable of forming cyanogen compounds, alloying said metal with another metal, separating the

first metal by vaporizing and reacting 65 upon the vapors with nitrogenous and carbonaceous matter.

5. The method of making cyanogen compounds consisting in electrolyzing a metallic compound containing a metal capable of 70 forming cyanogen compounds, alloying said metal formed with another metal, vaporizing the first metal in the presence of a current of nitrogen and reacting upon the vapor mixture with carbonaceous matter.

6. The method of making sodium cyanid consisting in vaporizing the sodium from an alloy and reacting upon the sodium vapors with nitrogenous and carbonaceous matter.

7. The method of making sodium cyanid consisting in vaporizing the sodium from an alloy in the presence of a current of nitrogen and reacting upon the sodium nitrogen vapors with carbonaceous matter.

8. The method of making sodium cyanid consisting in electrolyzing a sodium salt, alloying the sodium formed with another metal, separating the sodium from the alloy by vaporization and reacting upon the sodium vapors with nitrogenous and carbonaceous matter.

9. The method of making sodium cyanid consisting in electrolyzing a sodium salt, alloying the sodium formed with another 95 metal, separating the sodium from the alloy in the presence of a current of nitrogen and reacting upon the sodium nitrogen vapors with carbonaceous matter.

10. The method of making sodium cyanid 100 consisting in electrolyzing sodium chlorid, alloying the sodium with a cathode metal, separating the sodium from the alloy by vaporization and reacting upon the sodium vapors with nitrogenous and carbonaceous 105 matter.

11. The method of making sodium cyanid consisting in electrolyzing sodium chlorid, alloying the sodium with lead, separating the sodium from the alloy by vaporization 110 and reacting upon the sodium vapors with nitrogenous and carbonaceous matter.

12. The method of making sodium cyanid consisting in electrolyzing sodium chlorid, alloying the sodium with a cathode metal, 115 separating the sodium from the alloy by a current of inert gas and reacting upon the sodium with nitrogenous and carbonaceous matter.

13. The method of making sodium cyanid 120 consisting in electrolyzing sodium chlorid, alloying the sodium with lead, separating the sodium from the alloy by a current of inert gas and reacting upon the sodium with nitrogenous and carbonaceous matter.

14. The method of making sodium cyanid consisting in electrolyzing sodium chlorid, alloying the sodium with a cathode metal,

separating the sodium from the alloy by vaporization and reacting upon the sodium vapors with nitrogen and charcoal.

15. The method of making sodium cyanid consisting in electrolyzing sodium chlorid, alloying the sodium with lead, separating the sodium from the alloy by vaporization and reacting upon the sodium vapors with nitrogen and charcoal.

10 16. The method of making sodium cyanid consisting in electrolyzing sodium chlorid, alloying the sodium with a cathode metal, separating the sodium from the alloy by a current of inert gas and reacting upon the sodium with nitrogen and charcoal.

15 17. The method of making sodium cyanid consisting in electrolyzing sodium chlorid, alloying the sodium with lead, separating the sodium from the alloy by a current of inert gas and reacting upon the sodium with nitrogen and charcoal.

20 18. The method of making cyanogen compounds consisting in electrolyzing a molten compound of a metal capable of forming nitrogen compounds, alloying the separated metal with a cathode metal, removing the alloyed cathode metal and metal capable of forming a nitrogen compound and treating the last mentioned metal to separate at least a part of the same from the alloy as a metal *per se* and treating said separated metal with nitrogenous and carbonaceous matter.

25 19. The method of making cyanogen compounds consisting in electrolyzing a molten compound of a metal capable of forming nitrogen compounds, alloying the separated metal with a cathode metal, removing the alloyed cathode metal and metal capable of forming nitrogen compounds, separating at least a part of the last mentioned metal as a metal *per se*, from the alloy, treating said separated metal with nitrogenous and carbonaceous matter and returning the residual metal to the cathode.

30 20. The method of making cyanogen compounds consisting in continuously electrolyzing a molten compound of a metal capable of forming nitrogen compounds, alloying the separated metal with a cathode metal, removing the alloy, separating as a metal *per se* the constituent metal of said alloy which is capable of forming nitrogen compounds, from said alloy, reacting on the so-separated metal at a higher temperature with nitrogenous and carbonaceous reagents and returning the residual metal to the cathode.

35 21. The method of making cyanogen compounds consisting in continuously electrolyzing a molten compound of a metal capable of forming nitrogen compounds, alloying the separated metal with a cathode metal, removing the alloy, separating as a

metal *per se* the constituent metal of said alloy which is capable of forming nitrogen compounds, from said alloy and treating said separated metal with nitrogenous and carbonaceous matter.

40 22. The method of making cyanogen compounds consisting in continuously electrolyzing a molten compound of a metal capable of forming nitrogen compounds, alloying the separated metal with a cathode metal, removing the alloy, separating as a metal *per se* in the form of a vapor the constituent metal of said alloy which is capable of forming nitrogen compounds, from said alloy and treating said separated metal in the form of a vapor with nitrogenous and carbonaceous matter.

45 23. The method of making cyanogen compounds consisting in continuously electrolyzing a molten compound of a metal capable of forming nitrogen compounds, alloying said metal with another metal, removing the alloy, separating as a metal *per se* the constituent metal of said alloy which is capable of forming nitrogen compounds, from said alloy and treating said separated metal with nitrogenous and carbonaceous matter.

50 24. The method of making cyanogen compounds consisting in continuously electrolyzing a molten compound of a metal capable of forming nitrogen compounds, alloying said metal with another metal, removing the alloy, separating as a metal *per se* in the form of a vapor the constituent metal of said alloy which is capable of forming nitrogen compounds, from said alloy and treating said separated metal in the form of a vapor with nitrogenous and carbonaceous matter.

55 25. The method of making alkali-metal cyanogen compounds consisting in continuously electrolyzing a molten compound of the alkali-metal, alloying the separated alkali-metal with a cathode metal, removing the alloy, separating as a metal *per se* the alkali-metal from said alloy, reacting on said separated metal with a nitrogenous and a carbonaceous reagent and returning the residual metal to the cathode.

60 26. The method of making cyanogen compounds consisting in electrolyzing a molten compound of a metal capable of forming nitrogen compounds, alloying the separated metal with a cathode metal, removing the alloy, separating as a metal *per se* the constituent metal of said alloy which is capable of forming nitrogen compounds, from said alloy, reacting on the so-separated metal with nitrogenous and carbonaceous reagents and returning the residual metal to the cathode.

65 27. The method of making alkali-metal cyanogen compounds consisting in electrolyzing a molten compound of the alkali-

metal, alloying the separated alkali-metal with a cathode metal, removing the alloy, separating the alkali-metal as a metal *per se* from said alloy, reacting on the so-separated 5 alkali-metal with a nitrogenous gas and a carbonaceous reagent and returning the residual metal to the cathode

28. The method of making alkali-metal cyanogen compounds consisting in electrolyzing a molten compound of the alkali-metal, alloying the separated alkali-metal with a cathode metal, removing the alloyed cathode metal and the alkali-metal, separating the alkali-metal as a metal *per se* from 10 the alloy, converting the so-separated alkali-metal to an alkali-metal cyanogen compound by treatment with nitrogenous and carbonaceous matter and returning the residual metal to the cathode.

29. The method of making cyanogen compounds consisting in electrolyzing a molten compound of a metal capable of forming nitrogen compounds, alloying the separated metal with a cathode metal, removing the 15 alloyed first mentioned metal and cathode metal, separating as a metal *per se* the constituent metal of said alloy which is capable of forming nitrogen compounds, from said alloy and converting said separated metal 25 to a cyanogen compound by treatment with nitrogenous and carbonaceous matter.

30. The method of making alkali-metal cyanogen compounds consisting in forming a mass of molten matter, one constituent of which is the alkali-metal of an alkali-metal compound to be formed, by electrolyzing a molten salt of said alkali-metal and depositing the said alkali-metal electrolytically into a body of molten cathode material, treating the said mass of molten matter to separate at least a part of the so-incorporated alkali-metal therefrom as a metal *per se* and converting said separated part into a cyanogen compound by reacting the same with nitrogenous and carbonaceous matter.

31. The method of making cyanogen compounds consisting in forming a mass of molten matter, one constituent of which is a metal and another constituent of which is cathode material by electrolyzing a molten salt of the said metal and depositing the said metal electrolytically into a molten body of said cathode material, treating the said mass of molten material to separate at least 55 a part of the so-incorporated metal therefrom as a metal *per se* and converting said separated metal into a cyanogen compound by reacting upon said metal with nitrogenous and carbonaceous matter.

32. The method of making cyanogen compounds consisting in electrolytically liberating a metallic element capable of forming nitrogen compounds, in a chamber containing molten cathode metal to form an alloy,

comprising said element and said cathode 65 metal, conveying said liberated element while alloyed with said cathode metal to a second chamber, separating said element as a metal *per se* from said alloy and effecting a reaction in which said separated metallic 70 element, carbon and nitrogen participate.

33. The method of making cyanogen compounds consisting in electrolytically liberating a metallic element capable of forming nitrogen compounds, in a chamber containing 75 molten cathode metal, conveying said liberated element while alloyed with said cathode metal to a second chamber, separating said element as a metal *per se* from said alloy, effecting a reaction in which the said 80 separated element, carbon and nitrogen participate and returning the impoverished alloy to said first mentioned chamber.

34. In a method of making nitrogen compounds continuously electrolyzing a molten 85 compound of a metal capable of forming nitrogen compounds, alloying the separated metal with a cathode metal, removing the alloy, separating as a metal *per se* the constituent metal of said alloy which is capable 90 of forming nitrogen compounds, from said alloy and returning the residual metal to the cathode.

35. In a method of making nitrogen compounds continuously electrolyzing a molten 95 compound of a metal capable of forming nitrogen compounds, alloying the separated metal with a molten cathode metal, removing the molten alloy, separating as a metal *per se* in vaporous form the constituent 100 metal of said alloy which is capable of forming nitrogen compounds, from said alloy and returning the residual metal to the cathode.

36. In a method of making nitrogen compounds continuously electrolyzing a molten compound of a metal capable of forming nitrogen compounds, alloying the separated metal with a molten cathode metal, removing and heating the molten alloy, separating as 110 a metal *per se* in vaporous form the constituent metal of said alloy which is capable of forming nitrogen compounds, from said alloy and returning the residual metal to the cathode.

37. In a method of making nitrogen compounds continuously electrolyzing a molten compound of a metal capable of forming nitrogen compounds with a molten metal cathode, removing the molten cathode product, 120 separating as a metal *per se* in vaporous form the constituent metal of said cathode product which is capable of forming nitrogen compounds, from said cathode product and returning the residual molten metal to 125 the cathode.

38. In a method of making nitrogen compounds continuously electrolyzing a molten

compound of a metal capable of forming nitrogen compounds with a molten metal cathode, removing and heating the molten cathode product, separating as a metal *per se* in vaporous form the constituent part of said cathode product which is capable of forming nitrogen compounds, from said cathode product and returning the residual molten metal to the cathode.

In testimony whereof we have signed this 10
specification in the presence of two subscr-
ing witnesses.

HANS FOERSTERLING.
HERBERT PHILIPP.
